DESIGN FOR A BOTTLE

Meredith Stewart Ireys, Lancaster, Pa., assignor to Nelson, Baker & Company, Detroit, Mich., a corporation of Michigan

Application April 6, 1942, Serial No. 106,473

Term of patent 7 years

To all whom it may concern:

Be it known that I, Meredith Stewart Ireys, a citizen of the United States of America, residing at Lancaster, in the county of Lancaster and State of Pennsylvania, have invented a new, original, and ornamental Design for a Bottle, of which the following is a specification, reference being had therein to the accompanying drawing forming a part thereof, wherein:

I claim:

The ornamental design for a bottle, substantially as shown.

MEREDITH STEWART IREYS.
